(57) **CLAIM**

The ornamental design for a sweatshirt with bear logo, as shown and described.

DESCRIPTION

FIG. 1 is an isometric view of a sweatshirt with bear logo showing my new design;

FIG. 2 is a plan view thereof;

FIG. 3 is a front elevation view thereof;

FIG. 4 is a right side view thereof;

FIG. 5 is a left side view thereof;

FIG. 6 is a rear elevation view thereof;

FIG. 7 is a bottom plan view thereof; and,

FIG. 8 is an enlarged view of the bear logo of the sweatshirt with bear logo of FIG. 1.

The evenly spaced dash line shown in the drawings depict portions of the sweatshirt with bear logo that forms no part of the claimed design. The dash-dash-line in FIG. 8 depicts boundaries of the claim that form no part of the claimed design.

1 Claim, 5 Drawing Sheets

FIG. 1
